UNITED STATES PATENT OFFICE.

HENRY C. SERGEANT, OF WESTFIELD, NEW JERSEY, ASSIGNOR TO THE INGERSOLL-SERGEANT DRILL COMPANY, OF NEW YORK, N. Y., A CORPORATION OF WEST VIRGINIA.

GOVERNOR.

SPECIFICATION forming part of Letters Patent No. 738,634, dated September 8, 1903.

Application filed January 23, 1903. Serial No. 140,205. (No model.)

To all whom it may concern:

Be it known that I, HENRY C. SERGEANT, a citizen of the United States, and a resident of Westfield, in the county of Union and State of New Jersey, have invented a new and useful Improvement in Governors, of which the following is a specification.

My invention relates to an improvement in governors, and has more particularly for its object to provide a high-speed governor which is particularly applicable for use in connection with air-compressors and pumping-engines, the main object being to provide a governor which will be very sensitive in operation and may be operated with a small amount of friction.

A further object is to provide certain improvements in the construction, form, and arrangement of the several parts for insuring the successful operation of the governor.

A practical embodiment of my invention is represented in the accompanying drawings, in which—

Figure 1 represents the governor in side elevation with the parts in their normal position, the vertically-movable cut-off-controlling box being shown in section; and Fig. 2 is a top plan view of the governor, a portion of the cover of the box being broken away 30 to more clearly illustrate the parts within the box.

1 designates the driving shaft or spindle. A vertically-movable hollow box or casing surrounds the rotary shaft 1. To the bottom 2 of the box or casing is connected the upper end of a hollow shaft 3, which in turn supports the dash-pot rod 4 and cut-off rod 5. The cylindrical wall 6 of the hollow box projects upwardly from the bottom 2, forming the body portion of the box, and a cover 7 is provided for inclosing the box. A driving-sleeve 8 is fixed to the shaft 1 within the box by any suitable means, such as pins or screws 28, which sleeve is provided with a pair of outwardly-projected arms 9 and 10, having antifriction-rollers 11 and 12, each of which engages a track 13 for connecting the box to the shaft, so that it may be driven thereby, and at the same time permitted a vertically-

sliding movement along the shaft. I provide 50 a weighted toggle-joint connection between the box and the rotary shaft for controlling the rise and fall of the box according to the speed of the shaft, which connection is constructed, arranged, and operated as follows: The sleeve 55 8, which is fixed to the shaft 1 within the box, is provided with a pair of laterally-projected branches 14 15, to the free ends of which are hinged the upper ends of links 16 17.

Weighted arms 18 19 are hinged at 20 21 60 to the bottom 2 of the box and are also hinged at 22 23 to the lower ends of the links 16 17. In the present instance each of the weighted arms 18 19 comprises an elongated cylindrical portion provided with a lug 24, which 65 is hinged to a lug 25, uprising from the bottom 2 of the box by either the hinge-pintle 20 or the hinge-pintle 21, as the case may be. These weighted arms are further provided with cut-away portions 26 27 for receiving 70 the links 16 17 to permit the lower ends of the said links to be hinged at the centers of the cylindrical portions of the said weighted arms. The weighted arms 18 19 are hinged to the bottom 2 of the box a greater distance 75 from the rotary shaft than the points at which the upper ends of the links 16 17 are hinged to the branches 14 15 of the driving-sleeve 8.

When the governor is at rest, the hinged connections 22 23 between the weighted arms 8, 18 19 and the links 16 17 are in alinement with the hinged connections of the weighted arms with the bottom of the box and the hinged connections of the links with the driving-sleeve, thus forming a toggle-joint connection between the driving-sleeve and the box. Furthermore, the arrangement of the hinged connections of the several parts is such that the weighted arms exert a constant downward pressure upon the box, even when 90 the governor is at rest, for insuring the full movement of the cut-off device in this direction.

In the present form I have shown the branches 14 15 as being extended from the driving-sleeve 8 at right angles to the driving-arms 9 and 10 thereof, so as to leave ample room for the use of weighted arms 18 and

19 of the desired weight to suit different requirements.

By the use of the governor as hereinabove described I am enabled to provide a device 5 in which the friction incident to the engagement of the box with weighted rollers is obviated and am, furthermore, enabled to provide a device which will insure the return of the box to its normal position when the speed 10 of the shaft is not sufficient to operate the governor.

What I claim is—

1. In a governor, a rotary shaft, a vertically-movable hollow box driven thereby and 15 a weighted toggle-joint connection between the box and shaft.

2. In a governor, a rotary shaft, a driving-sleeve fixed thereto, a vertically-movable hollow box driven by the shaft and inclosing the 20 sleeve and a weighted toggle-joint connection between the box and the sleeve.

3. In a governor, a rotary shaft having a driving-sleeve fixed thereto, branches extended from the sleeve, a vertically-movable 25 hollow box driven by and inclosing the sleeve and weighted toggle-joint connections between the box and the said branches of the sleeve.

4. In a governor, a rotary shaft, branches 30 supported thereby, a vertically-movable hollow box driven by the shaft and weighted toggle-joint connections between the box and the said branches.

5. In a governor, a rotary shaft, branches 35 supported thereby, a vertically-movable hollow box driven by the shaft and weighted

toggle-joint connections between the bottom of the said box and the said branches.

6. In a governor, a rotary shaft, branches supported thereby, a vertically-movable hollow box driven by the shaft and weighted arms hinged to the bottom of the box and links connecting the arms and branches. 40

7. In a governor, a rotary shaft, a driving-sleeve fixed thereto having branches extended therefrom, a vertically-movable hollow box driven by said sleeve, weighted arms hinged to the bottom of the box and links connecting the arms to the said branches of the sleeve. 45

8. In a governor, a rotary shaft, branches supported thereby, a vertically-movable hollow box driven by the shaft, weighted arms hinged to the box, links connecting the arms to the branches, the hinged connections between the arms and the box being at a greater 55 distance from the shaft than the points of connection between the links and the branches.

9. In a governor, a rotary shaft, branches supported thereby, a vertically-movable hollow box driven by the shaft and toggle-joint connections between the branches and box arranged normally at an angle to the shaft. 60

In testimony that I claim the foregoing as my invention I have signed my name, in presence of two witnesses, this 2d day of January, 1903.

HENRY C. SERGEANT.
